UNITED STATES PATENT OFFICE.

IVAR RENNERFELT, OF DJURSHOLM, SWEDEN.

ELECTRIC FURNACE.

Application filed August 18, 1926, Serial No. 129,961, and in Sweden September 1, 1925.

My invention relates particularly to electric furnaces employing metallic resistors for generating the heat, and it has for its objects: First, to provide a furnace capable 5 of operating at a very high temperature; second, to provide means for obtaining a fairly uniform temperature; third, to facilitate assembling of the furnace; fourth, to cheapen the construction by using a multiple-unit system for building up the furnace 10 chamber; fifth, to facilitate removal or exchange of the heating resistors and, sixth, to provide means for securely, yet yieldingly, fastening the heating resistors to the 15 walls of the furnace chamber.

I attain the objects enumerated above by providing a furnace having a heating chamber made up of a plurality of heating elements, each consisting of a preferably unitary, flat frame or ring of refractory material, which on the inside edge is carrying the heating resistor, which may consist of a flat ribbon, a straight wire, a coil or spiral of wire or of any kind of a metallic resistor, 25 which may be used in electric heating ovens.

Each heating element may be considered as a transversal section of the furnace chamber, the number of the elements being determined by the length of the heating chamber, 30 the number of phases and the amount of heat to be generated. The heating element is made up of refractory bricks or plates, assembled in a frame of iron or any other suitable metal, and preferably provided with 35 a groove in the edge, which is turned inwards, so as to afford a certain protection to the resistor, being placed in said groove.

The resistors are made up of turns, surrounding the entire heating chamber, each 40 heating element carrying one or preferably several turns in series, as this means fewer terminal leads and, thus, a higher thermal efficiency. The terminals belonging to each turn or series of turns are brought out to 45 the outside of the furnace in a plane parallel to that of the flat frame or ring, supporting the resistors, and are then connected to a terminal board in any desired manner.

I prefer to use flat, rather thin ribbons 50 for generating the heat and to locate them with the flat side towards the furnace wall so as to get an unobstructed radiation of heat towards the interior of the furnace.

By arranging the resistors in this way I 55 am able to operate the furnace with only a small difference in the temperature of the

resistor itself and of the furnace chamber, which means an increase in the margin of safety for a certain furnace temperature. This is an important feature as the permissible working temperature of even the best grade of metallic resistor material is as a rule not over 1150 to 1175°, whereas it is often desired to be able to operate at a temperature of 1100° or even more in the fur- 60 nace chamber. 65

The resistors, ribbons, wires or coils, may be fastened to the refractory frame in any preferred manner. The ribbons may f. i. be kept in place by means of clamps of the same 70 ribbon material, surrounding the resistor and secured to certain places of the refractory body, constituting the heating unit. For this purpose small rivets or nails of the same material as the resistor itself may be 75 used, which are introduced into holes in the refractory material and fastened to this in any suitable way.

The invention is not limited to any certain shape of the refractory frames, which may 80 be circular, rectangular or of any other form as required for the furnace chamber.

The resistors may, furthermore, be divided into parts of a complete turn around the inside furnace wall, each part having its two 85 terminal leads on opposite places and not near each other as in the case of the resistors forming complete turns around the inside.

The accompanying drawing shows in two vertical sections a furnace embodying the 90 principal features of my invention.

Fig. 1 shows a rectangular frame at the lines X—X in Fig. 2, which represents a vertical section at the lines Y—Y in Fig. 1.

A resistor in the shape of a ribbon is indicated by 1 and a refractory body, supporting the ribbon, by 2. This body is made up of a plurality of suitably shaped bricks, held together by means of an iron hoop 3, so as to form a self-contained unit. By placing several 95 such units adjacent to each other a furnace 100 chamber of any desired length may be built up, having a square, oval or round cross section as the case may be. The resistor is connected to the power supply by means of terminals 4, projecting through the frame at the places indicated by 5 and well insulated 105 from the iron hoop, which holds the several parts together. Clamps of a piece of ribbon are indicated by 6. Said clamps are held in 110 place by means of nails or the like 7, projecting into holes 8 in the refractory mate-

rial. The resistors may also be fastened by means of wires or bands 9, surrounding the resistors and also a part of the refractory body, which may have holes 10, intended to receive the bands 9. Grooves 11 may be provided in the refractory body in order to afford protection to the resistors. The object to be heated may be placed on a plate 12 of heat resisting material, which may be 10 developed into a muffle.

The system of heating elements making up the furnace chamber may be surrounded by a steel plate shell in any preferred manner. This outside shell is not shown on the 15 drawing, as it is more or less immaterial to the invention.

The heating elements as described above may be used in furnaces having a horizontal heating chamber as well as in furnaces having a vertical chamber, in which f. i. a crucible may be located for melting anything not requiring a temperature above 1150° or thereabout.

Having now fully described my invention, 25 I claim and desire to secure by Letters Patent of the United States:

1. In an electric furnace a refractory, frame shaped flat body, a ribbon resistor located concentrically along the inner edge of 30 the body, and means for securely clamping and reinforcing the body on the outside edge.

2. In an electric furnace the combination of a refractory body in the shape of a flat 35 frame with a resistor, preferably in the shape of a ribbon, straight and securely at-

tached to the said body concentrically along the inner edge of the refractory body, and located in a protecting groove, the walls of which project inwards beyond the resistor, 40 the ends of which are brought out of the furnace at right angles to the longitudinal axis of same.

3. In an electric furnace a refractory, frame shaped flat body, a ribbon resistor located concentrically along the inner edge of 45 the body and means for securely clamping and reinforcing it to the said body, the ends of the resistor being brought out of the furnace at right angles to the longitudinal axis 50 of same.

4. In an electric furnace the combination with each other to a heating chamber, of a plurality of frame-shaped refractory flat bodies, having heating resistors straight and 55 securely attached concentrically along the inner edges, the ends of each resistor being brought out of the furnace at right angles to the longitudinal axis of same.

5. In an electric furnace a frame-shaped, 60 refractory flat body in combination with a heating resistor located concentrically along the inner edge of the body and securely attached to the body by means of clamps which are in any suitable manner secured to the body, the ends of the resistor being brought 65 out of the furnace at right angles to the longitudinal axis of same.

Signed at Stockholm in the county of Stockholm Lan and State of Sweden this 70 6th day of August A. D. 1926.

IVAR RENNERFELT.
